Primary Examiner — Kendra Leslie Hamilton(74) *Attorney, Agent, or Firm* — MLO, a professional corp.(57) **CLAIM**

The ornamental design for a sleeve for a baby bottle, as shown and described.

DESCRIPTION

FIG. 1 is a top, rear, left perspective view of a sleeve for a baby bottle, showing our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

In the drawings, the broken lines depict environmental structure and form no part of the claimed design.
